UNITED STATES PATENT OFFICE.

CLINTON C. BUTLER, OF WATERLOO, IOWA, ASSIGNOR, BY MESNE ASSIGNMENTS, TO
GEO. W. DICKINSON, OF WATERLOO, IOWA.

GAS-PRODUCER FOR EXPLOSIVE-ENGINES.

1,152,003.

Specification of Letters Patent. Patented Aug. 31, 1915.

Application filed July 31, 1913. Serial No. 782,360.

To all whom it may concern:

Be it known that I, CLINTON C. BUTLER, a citizen of the United States of America, and a resident of Waterloo, Blackhawk county, Iowa, have invented certain new and useful Improvements in Gas-Producers for Explosive-Engines, of which the following is a specification.

My invention relates to improvements in gas-producers for internal-combustion engines, and the object of my improvement is to provide means for generating a gas of the proper specific gravity for complete combustion from kerosene or the heavier petroleum products, such means being so located and associated with the combustion-chamber of an engine as to borrow heat by conduction and radiation therefrom, to act conveniently and without loss of energy, and with a maximum efficiency. This object I have accomplished by the means which are hereinafter described and claimed, and which are illustrated in the accompanying drawings, in which:

Figure 1 is a horizontal central section of the combustion-chamber part of the cylinder of an explosive-engine and of my auxiliary gas-producer chamber, its valve and the communications between it and said combustion-chamber. Fig. 2 is an elevation of the end of said gas-producer chamber as mounted on said combustion-chamber. Fig. 3 is a detail view of the interior of a gas-producer chamber of a variant form, with the head removed, and parts broken away.

Similar numerals of reference denote corresponding parts throughout the several views.

The engine-cylinder 1 is represented as being horizontal, containing a piston 2, and its combustion-chamber 3 is provided with both inlet- and exhaust-ports, closed by means of the resiliency-controlled inlet- and exhaust-valves 16 and 18 respectively. The combustion-chamber also contains a spark-plug 21. The exhaust-valve 18 is actuated by any suitable means at proper times, to exhaust the burned gases from said combustion-chamber into the outlet-chamber 20. The inlet-valve 16 is actuated on the suction-stroke of the piston 2 in the usual way. A common passage 17 intervenes between the combustion-chamber and the inlet- and exhaust-ports. The cylinder-head 4 is formed to coöperate in use with an auxiliary spaced

head 9, secured detachably thereto, and is secured by bolts and nuts 22—23. As shown in Fig. 1, both said heads have spaced vertical ribs, 5 and 8 respectively, which, however, are alternated in such a fashion as to permit the ribs on each head to lie between and spaced from the ribs on the other head to provide a zigzag passage 11 therebetween, uninterruptedly from an inlet-tube 10 to an outlet-channel 12. The head 9 is detachably secured to a thickened rib 6 on the head 4 by means of a screw 7. The channel 12 delivers into the hollow 15 of a storage chamber 19 by way of the transverse opening 14 of a rock-valve 13 when the latter has been rocked to open into said chamber, and the inlet-port of the combustion-chamber is in the inner wall of said chamber 19. The storage-chamber 19, when the valve 13 is rocked to a closed position, retains a charge of the relatively heavy gaseous combustible ready for admission to the combustion-chamber when the valve 16 is moved to open said inlet-port, which prevents a backward escape of gas into the passage 11, since the said valves must be alternately moved to fulfil this function.

The inlet-tube 10 is in communication with a carbureter not shown, which has supply-pipes to separate reservoirs of kerosene and gasolene, with the communication controlled by a suitable valve adapted to permit either fluid to be used. The starting of the engine is effected when the gasolene has been first supplied to the carbureter and the latter delivering its gas to the tube 10 and passage 11, the mixed gasolene vapor and air passing unchanged through the valve-opening 14, to be delivered in the usual way by way of the chamber 19 and inlet-port past its valve 16 to the combustion-chamber 3. After the engine is thus started by the use of gasolene the gasolene is shut off from the carbureter and kerosene introduced therein. The dense, relatively heavy vapor of the kerosene (or other heavier petroleum product used) is then drawn through the zigzag passage 11, and since the cylinder-head has become considerably heated the heavy vapor is held long enough in the passage to become raised in temperature to cause its particles to become split up into relatively minute parts, or placed in a true gaseous condition, which, when the valves 13 and 16 are alternately moved to permit

its transmission to the combustion-chamber 3, moves into said chamber in a consistency much like that of the vaporous gas of the lighter hydrocarbons, there to be ignited and completely consumed in the usual way. The alternated spaced ribs in the gas-producer chamber 9 therefore force the vapor through a longer channel and communicate thereto heat from their multiplied surfaces, by both conduction and radiation.

In Fig. 3 is illustrated a slightly varied type of my invention, in which the gas-producer chamber part 24 is the combustion-chamber head of the cylinder 1, and this view shows the cover removed, the latter being a mere flat covering-plate provided with an inlet-tube like that shown in Fig. 1 at 10, but placed centrally in order to communicate directly with the inner end 30 of the zigzag passage 29. The latter passage delivers at 25 to a valve 18, chamber 19, and by way of a valve 16 to the combustion-chamber, the latter parts not being shown in the figure. The passage 29 in the chamber 24 is arranged about a spiral wall 26. The said wall, as also its continuation wall 24, has L-shaped baffling projections 28 alternated with like projections 27 in such a fashion that they extend between each other to leave openings in their ends to produce a zigzag passage. The kerosene vapor introduced into the inner end 30 of the passage 29 is forced to flow to the passage 25 the full length past the projections 27 and 28, which, however, do not prevent the free movement of the vapor, being arranged with their outer angles toward the flow of the current. The vapor is thus in a similar manner heated sufficiently while held in said long passage to be broken into gaseous molecules for complete combustion without partial condensation in the combustion-chamber.

I do not wish, however, to be understood

as confining myself strictly to the forms specifically shown herein, for it is obvious that many other specific forms may be made which will come within the general scope and principle of my invention.

50

What I claim as new, and desire to secure by Letters Patent, is:

1. A removable gasifying cylinder-head for an internal-combustion engine containing a gasifying chamber in communication with a carbureter, and a reserve-supply chamber, the former being in communication with the latter chamber by means of a valve-controlled port, and the latter chamber being in communication with the combustion-chamber of the engine by means of a valve-controlled port, the valves in said ports being adapted to work alternately, to permit a reserve supply of heated gas to be stored in said supply-chamber and prevent its escape therefrom back into the gasifying chamber.

60

2. A removable gasifying cylinder-head for an internal-combustion engine, containing a gasifying chamber provided with projections of its inner walls into its interior to form a convoluted passage therein, and having a communication with the carbureter, said cylinder-head also containing a reserve-supply chamber in communication with said gasifying chamber by means of a valve-controlled port, and also being in communication with the combustion-chamber of the engine by means of a valve-controlled port, the valve in the latter port being adapted for opening alternately with the opening of the former valve, to secure a charge of gas in the latter chamber and prevent its back movement into the gasifying chamber.

70

Signed at Waterloo, Iowa, this 12th day of July, 1913.

CLINTON C. BUTLER.
